CLAIM

The ornamental design for a handle for a pipe wrench, as shown and described.

DESCRIPTION

FIG. 1 is a front view of a handle for a pipe wrench; the opposite side to that shown being a substantial mirror image; FIG. 2 is a right side view of the handle for a pipe wrench of FIG. 1;

FIG. 3 is a left side view of the handle for a pipe wrench of FIG. 1;

FIG. 4 is a top view of the handle for a pipe wrench of FIG. 1; FIG. 5 is a bottom view of the handle for a pipe wrench of FIG. 1;

FIG. 6 is a right-front perspective view of the handle for a pipe wrench of FIG. 1; and,

FIG. 7 is a bottom-right perspective view of the handle for a pipe wrench of FIG. 1.

It is to be understood that those portions shown in broken lines in the accompanying figures do not constitute a part of the subject design and are for illustrative purposes only.
